BALL COCK

John J. Delany, Brooklyn, and Edwin C. Baisel,
New York, N. Y., assignors to Delany Realty
Corporation, New York, N. Y., a corporation of
New York

Application June 4, 1947, Serial No. 752,410

1 Claim. (Cl. 137—104)

1

This invention relates to ball cocks for controlling the water supply to flush tanks of closet bowls and the invention has particular reference to a ball cock which is substantially silent in operation and which is non-syphoning.

The invention has for an object the provision of a ball valve which functions to reduce the velocity and pressure of the water passing therethrough so that the same is discharged without kinetic energy or velocity. It has been determined that the noise produced by the discharge of water from ball cocks has been due to the high velocity and pressure of the water at the discharge orifice. In order to overcome this objection and to produce a substantially silent valve, the present invention reduces both the pressure and velocity of the water so that the same is discharged gravitationally in a downwardly directed stream from a discharge outlet located above the level of the water in the tank.

The invention has for a further object the provision of a ball cock having means for cushioning and for reversing the direction of flow of the water through the valve port thereof.

The invention also has for an object the provision of an adjustable valve element for regulating the volume of water flowing through the ball cock.

Another object of the invention resides in the provision of a refill tube connected with the valve cock adjacent the discharge outlet.

Still another object of the invention is the provision of an integral valve body having a water passageway of continuously increasing cross-sectional area extending from the valve port to a discharge chamber located above the level of the water in the tank and formed with a bottom discharge outlet.

With the foregoing and other objects in view, reference is now made to the following specification and accompanying drawings in which the preferred embodiment of the invention is illustrated.

In the drawings:

Fig. 1 is a view in elevation of a ball cock constructed in accordance with the invention and illustrating the same in applied position in a flush tank with the tank shown in fragmentary sectional view.

Fig. 2 is a vertical sectional view through the ball cock.

Fig. 3 is a horizontal sectional view thereof taken approximately on line 3—3 of Fig. 2.

Referring to the drawings by characters of reference, the ball cock 10 is adapted to be

2

mounted on the upper end of a water supply pipe 11 located within and extending upwardly through the bottom wall of the usual flush tank 12 as illustrated in Fig. 1 of the drawings. The ball cock is automatically actuated by a ball float 13 for refilling the tank with water after each flushing of the toilet bowl. Connected with the ball cock is a refill tube 14 having its free open end extending into the upper end of the usual overflow pipe 15 so as to provide for a continuous discharge to the overflow pipe of a portion of the water passing through the ball cock during each filling of the tank.

The ball cock consists of a body 16 formed with a cylindrical bore 17 opening through the upper and lower ends thereof and which is in communication through an opening 18 adjacent the lower end thereof with an elongated chamber 19 and through an opening 20 adjacent the upper end of the chamber 19 with a discharge chamber 21.

The lower portion of the cylindrical bore 17 forms a valve chamber for regulating the flow of the water from the supply pipe 11 while the opening 18, chamber 19, opening 20 and discharge chamber 21 form a passageway for reducing the velocity and pressure of the water admitted through the valve chamber for discharge thereof from the discharge chamber at a minimum velocity and pressure. In order to produce the aforesaid reduction in velocity and pressure, the said passageway progressively increases in cross-sectional area from the valve chamber to the discharge chamber, thus the cross-sectional area of the chamber 19 is relatively larger than the cross-sectional area of the opening 18 and the cross-sectional area of the opening 20 is relatively larger than the cross-sectional area of the chamber 19 while the cross-sectional area of the discharge chamber 21 is relatively larger than the cross-sectional area of the opening 20.

Mounted for vertical reciprocating movement within the bore 17 is a valve element 22 formed with an annular recess 23 in the lower end thereof of which recess is provided with a conical shaped wall 24 at the upper end thereof against which is disposed a flexible resilient disk 25. A bushing 26 is threadedly engaged in the lower end of the bore 17 and secures the ball cock 10 on the upper end of the supply pipe 11. The bushing 26 is formed with a reduced upper end 27 which extends into the annular recess 23 in the lower end of the valve element 22 with the upper end edge of said reduced portion 27 forming a valve seat 55 adapted to be engaged by the disk 25 for shutting

off the flow of the water through the ball cock when the valve element 22 is in its lowermost position.

The valve element 22 is moved toward and away from the said valve seat by the movement of the ball float 13. The ball float 13 is secured to the outer free end of a lever arm 28 which is pivoted for vertical swinging movement on a pivot pin 29 located in apertured lugs 30 formed integrally with the body 16 with the inner end of the lever arm protruding through a vertical slot 31 between the lugs 30 in the body 16 and connected with the valve element 22 by a ball and socket connection 32. A screw cap 33 threadedly engaged in the upper end of the bore 17 is adjustable therein for setting the valve element 22 for admitting the described flow of water between the upper end of the bushing 26 and the disk 25. The screw cap 33 also provides a stop for limiting the downward swinging movement of the ball float 13.

In order to prevent direct discharge of the water from the discharge chamber 21 and to cause the same to be discharged therefrom in relatively fine water particles a length of corrugated or plaited wire screen 34 is formed into helical formation and arranged within the discharge chamber 21 adjacent the outlet 35 thereof. The screen 34 is arranged endwise or vertically within the discharge chamber 21 and the body 16 is formed with an inwardly directed annular lip 36 providing a shoulder on which the outermost convolution of the screen is disposed to support the same.

The refill tube 14 is connected with the discharge chamber adjacent the outlet 35 and below the top of the screen 34 so that in the event a vacuum occurs in the water supply line 11 the vacuum produced in the discharge chamber will be broken by the intake of air through the outlet 35 to thus avoid any appreciable degree of suction occurring in the refill tube 14. The refill tube 14 being connected with the discharge chamber 21 below the top of the screen 34 or with the screen 34 in covering relation with the opening into the refill tube 14 permits only a limited amount of water to flow through the refill tube.

It will be understood that the reduced upper end 27 of the bushing 26 projecting into the annular recess 23 in the lower end of the valve element 23 provides a relatively narrow port for the flow of the water therebetween and which produces a reversal of the direction of flow of the water while the conical formation of the upper face 24 of the recess 23 provides means whereby the bushing 26 will be flexed into conical formation by the force of the water admitted through the upper end of the bushing 26 to thereby provide a cushioning and dampening action of the water admitted therethrough.

The body 16 is preferably formed as a casting with three parallel cavities which open through the upper end thereof. This permits of the ma-

ching of the cavities through the open ends so as to provide the bore 17, chamber 19 and discharge chamber 21 with smooth inner surfaces for the flow of the water. The chamber 19 and the discharge chamber 21 are then closed at their upper ends by means of screw plugs 37 and 38. In addition thereto the screw plugs 37 and 38 may be readily removed to permit of the cleaning of the chamber 19 and discharge chamber 21, while the screw plug 38 also permits of the convenient insertion and removal of the screen 34.

What is claimed is:

In a ball cock, a valve body having a circular valve chamber, a valve seat located in said valve chamber and defining a valve port through which water is admitted, a valve element located in said valve chamber and movable toward and away from said seat for regulating the flow of water therethrough, said valve body having a discharge chamber of relatively larger cross-sectional area than said valve chamber and being provided with a downwardly directed discharge outlet located above the valve port, a passageway in said valve body extending from said valve chamber below said valve seat to said discharge chamber adjacent the top thereof, said passageway being of progressively increasing cross-sectional area in the direction of flow of the water for reducing the pressure and velocity of the water flowing from the valve chamber to the discharge chamber, said valve body having an opening adjacent the outlet of said discharge chamber for receiving a refill pipe, and a screen located in said discharge chamber over said discharge outlet through which the water is discharged in relatively fine water particles and said screen being disposed in covering relation with the opening for said refill pipe for preventing too free flow therethrough.
